UNITED STATES PATENT OFFICE.

JOHN RAUS, OF CLEVELAND, OHIO, ASSIGNOR, BY MESNE ASSIGNMENTS, TO THE NATIONAL FORMETAL COMPANY, OF CLEVELAND, OHIO, A CORPORATION OF OHIO.

FIRE EXTINGUISHER.

Application filed January 22, 1923, Serial No. 614,123. Renewed May 21, 1927.

This invention relates to fire extinguishing apparatus and has for its object the provision of a small and comparatively inexpensive extinguisher for domestic, factory and indoor use which shall be so small as easily to be carried and conveniently operated; in which the charge can be conveniently stored, shipped and handled; wherein the deterioration of the extinguisher and its contents during the idleness shall be a minimum; the provision of an extinguisher whose use shall serve effectively to extinguish fires but without injury to paint or varnish or danger of asphyxiation; while further objects and advantages of the invention will become apparent as the description proceeds.

In the drawings accompanying and forming a part of this application I have shown one embodiment of my said invention, but without intent to limit myself thereto since many changes can be made without departing from the scope of my inventive idea. In these drawings Fig. 1 is a front elevation 25 of my improved extinguisher together with its supporting bracket; Fig. 2 is a central sectional view of the extinguisher and bracket corresponding to the line 2—2 of Fig. 1; Fig. 3 is an enlarged detail sectional view 30 of the upper end of the extinguisher showing the acid capsule partly in section; Fig. 4 is a horizontal sectional view corresponding to the line 4—4 in Fig. 1; Fig. 5 illustrates the blank from which the acid capsule is made; Fig. 6 illustrates the mode of forming the base of the capsule; Fig. 7 illustrates the mode of forming the mouth of the capsule and Fig. 8 illustrates a modified construction of capsule.

Describing the parts by reference characters, 1 represents the body of the can or container, preferably of about one or two quarts capacity, although the size is not restricted, having at one end the closed cap 2, and handle 3 and at the opposite end the apertured cap 4. Located near the cap 4 at one side of the container is the transverse nozzle 5 which is located as near the end of the container as possible.

The cap 4 has an axial aperture surrounded by the threaded flange 6 on which is screwed the bonnet 7 also provided with a hollow neck 8 in which is slidably mounted the shank 9 of a plunger. This plunger 55 is formed inside the bonnet with an enlarge-

ment 10 and outside thereof with a head 11, between which and the bonnet is interposed the spring 12, the inner face of the bonnet being covered by a suitable packing disk 13 which prevents leakage at either edge of the same. The outer end of this bonnet is preferably counterbored for a packing washer 14 and a metal washer 14^a, the latter being engaged by the spring 12 which holds it in place and exerts the desired sealing pressure on the washer.

Located in the flange 6 is a removable thimble 15 having at its inner end an in-turned lip 16 and at its outer end an out-turned lip 17 which overlies the flange, a suitable packing ring 18 being placed beneath the same. The walls of this thimble are formed with ports or apertures 19.

Removably seated in the thimble 15 is the acid capsule 20 which consists of a cylindrical body having at its end the external flange 21 which engages the lip 16 and a transverse end wall 22 having opposite the end of the plunger a portion 23 of decreased thickness. The end of the plunger is formed with a piercing point 24 and suitable means are employed to hold the capsule against the flange 16 at all times, such means in the present case comprising a spring 25 secured to the enlargement 10 and pressing against the capsule.

The bracket here shown comprises a base plate 30 adapted to be secured to a wall or like support having at its upper end a pair of spaced vertical plates 31 between which the plunger 9 is inserted, the width of these plates being such as to fill the space between the top of the bonnet 7 and the bottom of the head 11. At the other end the bracket is formed with a spring finger 32 having at its end a knob 33 adapted to engage a groove 34 formed in the cap 2. Projecting from the side of the bracket is another spring arm 36 provided with a cushion 35 of sealing material such as rubber adapted to engage the nozzle and closing the same so as to prevent loss of contents of the container.

This container is filled substantially full of a solution of baking soda, with or without additional substances like certain aluminum salts to produce foaming; the capsule 20 is filled with a suitable acid substance such as sulphuric acid or hydrochloric acid, and hermetically sealed thereby preventing either loss of contents, ingress of moisture or pre-

mature actuation. The construction of the bracket holds the extinguisher in such wise as to prevent accidental actuation of the plunger or leakage and evaporation of liquid. Upon the necessity of use the device is removed from the bracket by a simple pull thereby unsealing the nozzle and releasing the plunger which is thereupon struck smartly upon the floor or some convenient object, puncturing the weakened portion of the acid capsule so as to permit the gradual escape of its contents. The springs 12 and 25 effect the immediate withdrawal of the plunger from obstructing position and seal the bonnet against leakage by pressing the enlargement 10 against the packing 13. The comparatively slow escape of the acid from the small perforation made by the plunger causes the gas pressure inside the container to remain substantially constant during the entire operation of the device and also causes the ejected liquid to possess a substantially uniform, non-corrosive composition.

This acid capsule is preferably made of lead owing to its cheapness, its softness and its non-corrodible nature. It is preferably made by casting or die forming a cartridge as shown in Fig. 5 with a cylindrical wall 40 and one closed end 41 of somewhat greater thickness than the wall.

A cylindrical mandrel 42 is then inserted into the cartridge, said mandrel having at one end the central boss 43 and being of exactly the requisite length; and the cartridge and mandrel are inserted into a cylindrical recess of a die block 44 which exactly receives the same, the upper end of this recess being counterbored as shown at 47. The upper end of the cartridge is then struck with the movable member 45 of the punch press which displaces the metal of the closure 41 laterally into the recess 47 forming the flange 21 and also produces the central region of reduced thickness shown at 23 in Fig. 3.

The open mouth of the cartridge is then swaged, drawn, or spun to form a narrow neck 48 which, after the capsule is filled with acid, is collapsed and folded as shown at 49, being further sealed against leakage by soldering, if desired. According to a modification of my idea the body of the capsule is made of glass as shown at 50 in Fig. 8, having at its open end an external lip 51 adapted to receive a tightly fitting closure cap 52 whose center is formed with a weakened or perforable portion 53 and whose lip is crimped over the flange 51 as shown at 54. This arrangement is preferably for large size installations such as those used for factories, and fire departments.

While I have illustrated my improvements as applied to a small sized device, it will be understood that many features of the same can equally and advantageously be applied to the large devices used by factories, fire departments, etc., wherefore I do not restrict myself to any dimensions, nor to any matters of detail or construction except as specifically recited in my claim.

Having thus described my invention, what I claim is:

The combination with a fire extinguisher comprising a liquid container having a nozzle near one end, a reciprocable plunger projecting from one end, and a handle at the opposite end, of a bracket having near one end a pair of arms adapted to secure said plunger in supporting and movement preventing relation, a flexible arm at the opposite end of said bracket to engage said receptacle yieldingly, and a spring arm projecting laterally from one side of said bracket and having at its free end a pad adapted to cover said nozzle.

In testimony whereof, I hereunto affix my signature.

JOHN RAUS.
